UNITED STATES PATENT OFFICE.

JOSE JOAQUIN, OF SAN JOSE, CALIFORNIA.

ROOF TILE.

Application filed August 18, 1924. Serial No. 732,743.

To all whom it may concern:

Be it known that I, JOSE JOAQUIN, a subject of Portugal, residing in the city of San Jose, county of Santa Clara, and State 5 of California, have invented a new and useful Improvement in a Roof Tile, of which the following is a specification.

My invention relates to improvements in tiles for roofs and the like wherein upper 10 tiles are provided with flanges arranged to overlap each other and to interlap corresponding overlapping flanges of lower tiles to form a roof.

The primary object of my invention is to 15 form an improved tile for roofs.

Another object is to provide an improved construction which will facilitate the laying of a roof and which will afford an efficient weather and fire proof roofing.

20 A further object is to provide an improved tile which may be easily mounted from cement or other suitable material at a nominal cost.

Another object is to provide a tile having improved means for holding the same upon a roof and for regularly spacing the tiles.

25 A still further object is to provide an improved construction whereby tiles constituting a roof may be caused to overlap and interlap in close matching relation whereby a large area of contact will be afforded between adjacent tiles.

I accomplish these and other objects by 30 means of the device disclosed in the drawings forming a part of the present specification wherein like characters of reference are used to designate similar parts throughout said specification and drawings and in 35 which,

Fig. 1 is a broken side elevation of a portion of a roof showing the manner in which my improved tiles are laid thereon.

Fig. 2 is a longitudinal sectional view 45 taken upon the line 2—2 of Fig. 1 in the direction indicated.

Figs. 3 and 4 are transverse sectional views taken upon the line 3—3 and 4—4 respectively of Fig. 2 in the direction indicated.

Fig. 5 is a bottom view of an upper tile.

Fig. 6 is a longitudinal mid-section of the tile shown in Fig. 5.

Fig. 7 is a top view of a bottom tile.

55 Fig. 8 is a longitudinal mid-section of the tile shown in Fig. 7.

Referring to the drawings my invention will be seen to consist of upper and lower tiles designated in general by the numerals 1 and 2 respectively. The tiles consist of 60 flat body portions the longitudinal edges of which converge toward one end thereof. Flanges 3 are formed upon the converging edges of the tiles at substantially right angles to the plane of the body portions. 65 The ends of the flanges 3 at the narrow end of each tile are cut away to form notches 4. The flanges converge to a degree such that the narrow end of each tile may be received between the flanges at the wide end 70 of an adjacent tile whereby said tiles may be laid in overlapping relation, the notches 4 being of a depth equal to the thickness of the body portion of the tile and of a length equal to the distance to which the tiles may 75 be caused to overlap so that the upper edges of the overlapping portions of the flanges will be in substantially the same plane.

Lugs 6 are formed upon the under side 80 of the lower tiles 2, and a lug 7 is formed upon the under side of each upper tile 1. The lugs 6 and 7 are formed at substantially right angles to the plane of the body and extend downwardly to engage the upper 85 edges of transverse cleats 8 forming part of a supporting structure upon which the tiles are laid. The lug 7 also serves as a spacing element by which the adjacent ends of the lower tiles are laid in regularly spaced relation.

The tiles are laid to form a roof as shown in Fig. 1 of the drawings, the lower tiles 2 being laid in spaced relation with their flanges upwardly disposed and the lugs 6 hooked over the edges of the cleats 8 of the 95 supporting structure. The narrow end of the tiles 2 are placed downwardly with respect to the inclination of the roof. The tiles are laid successively from the lower edge of the roof upwardly, the narrow end 100 of each tile 2 being placed in overlapping relation with the wide portion of the next lower tile.

The upper tiles 1 are laid over the lower tiles 2 with the flanges 3 of said upper tiles disposed downwardly, each tile 1 spanning the space between adjacent lower tiles 2 and having the lug 7 hooked over the cleat 8 between said lower tiles, which are moved closely against the sides of the lug 7 to obtain uniform spacing. The narrow ends of 110 the upper tiles 1 are disposed upwardly

with respect to the inclination of the roof, the wide portion of each upper tile being caused to overlap the narrow end of the next lower tile 1. When laid in this manner each row of upper and lower tiles will overlap the corresponding tiles of the next lower row and the downwardly disposed flanges of the upper tiles 1 will be caused to interlap with the upwardly disposed flanges 10 of the lower tiles 2 as shown in Figs. 3 and 4 of the drawings. The notches 4 of each upper tile receive the overlapping ends of the adjacent lower tiles, and in like manner the notches of the lower tile flanges receive 15 the overlapping ends of the upper tiles thereby permitting the interlapping ends of the flanges to nest closely together and insures a large area of contact between the overlapping surfaces of the tiles.

20 In my present practice the tiles are preferably moulded from cement in suitable forms, the tiles thus formed being thoroughly fire and weather proof. Tiles thus formed have great strength and durability 25 and are particularly adapted to withstand rough handling without damage to the tiles. Furthermore, the forming of tiles in this manner may be carried out very economically, thereby affording a highly efficient 30 roofing material at a moderate cost. The cement from which the tiles are moulded may be readily colored by means of various pigments, thus affording a wide selection of colors whereby a roof may be made of a desired 35 color or decorative character. However, tiles of similar construction and utility may be made from other materials without departing from the spirit of my invention, and the specific details of construction 40 above disclosed may be modified in a number of ways. I therefore do not wish to restrict myself to the precise details of structure but wish to avail myself of such modifications as may fall within the scope 45 of the appended claims.

Having thus described my invention what I claim as new and desire to secure by Letters Patent is,

1. In a tile roof, upper and lower tiles

having oppositely disposed flanged edges, 50 the flanged edges of said upper and lower tiles converging in opposite directions and having notches formed in the flanges at the narrow end of each tile whereby portions of the flanges at the narrow end of each tile 55 may be received between overlap portions of the flanges at the wide end of an adjacent overlapping tile and the overlapping flange portions interlap with the overlapping flange portions of opposite tiles; and lugs 60 formed upon the under sides of the upper tiles to engage and retain said tiles upon a supporting surface, said lug forming a spacing element adapted to space the ends of the underlying tile.

2. In a tile roof, lower tiles having converging longitudinal edges; upwardly disposed flanges formed upon said converging edges and having notches formed in the flanges adjacent the narrow end of each tile, 70 the narrow end of each tile being adapted to overlap the wide end of an adjacent tile and portions of the flanges at said narrow end to be received in overlapping relation with portions of the flanges upon said wide end: upper tiles having converging longitudinal edges; downwardly disposed flanges formed upon said edges and having notches formed adjacent the narrow end of each tile, the wide portion of each upper tile being adapted to overlap the narrow portion 75 of an adjacent upper tile with portions of the flanges overlapping, the overlapping flange portions of said upper tiles being adapted to interlap with the overlapping flange portions of the under tiles, and the notches adapted to receive the interlapping ends of the tiles; and lugs formed upon the under sides of the upper and lower tiles to engage and retain the tiles upon and inclined supporting surface, the lugs upon the upper tiles being received between adjacent lower tiles to independently engage the supporting surface and to form a spacing element for said adjacent lower tiles.

In witness whereof I hereunto set my signature.

JOSE JOAQUIN.
